UNITED STATES PATENT OFFICE.

NIXON LEE, OF BROOKLYN, NEW YORK.

CLOSURE.

Application filed December 3, 1923. Serial No. 678,164.

My invention relates to closures used for sealing the openings in containers, jars or bottles in which the closure is adapted to be repeatedly applied to and removed from the container, and furthermore to tightly seal the container when the closure is affixed and locked in sealing position, even after repeated applications and removals.

My improved closure construction is particularly adapted for use with bottles or jars having separated or divided spiral threads lying on the outer surface of the neck to coact with bent-in locking projections formed in the depending skirt or flange of the closure cap.

The primary object of my invention is, among other things, to provide an improved closure of this type whereby the closure cap may be economically strengthened or reinforced, while the bent-in locking projections are formed in the skirt in different planes relatively to the crown of the cap, and preferably of different sizes or lengths, to coact with respectively different sections of the divided spiral thread or threads formed on the bottle neck, such sections being relatively spaced-apart from each other to allow for the downward passage of the particular locking projections before the closure is rotated and locked in position. Furthermore by this improved structure with such coaction between the engaging parts of the closure cap and bottle neck pitches of small amount relative to the thickness of the threads may be obtained. Such slight pitches do not prevent a firm and secure locking action and take care of liner or gasket shrinkage, while the degree of pitch of such a divided spiral thread may be brought much nearer the horizontal than in that type of closures or caps having punched-in portions engaging separated and multiple spiral threads which lie substantially in mutual parallelism with one another on the outer surface of the bottle-neck. Hence such a pitch plane may be even less than the width of such spiral thread on the bottle neck, and it is of advantage to have the pitch of such thread approach the horizontal not only to increase the wedging action between the parts to secure a tight seal, but also to pre-

vent the cap closure from being inadvertently rotated or "backed off" the container during handling and transportation.

With the above and other objects in view, my invention comprises the novel construction, combination and arrangement of parts to be hereinafter described and claimed.

In the drawings showing embodiments of my invention—

Fig. 1 is a sectional elevation of the glass container and closure cap in locked position;

Fig. 2 is a development, more or less diagrammatic in form, of the closure cap showing the relative location of the locking projections bent in from the depending skirt of the cap;

Fig. 3 is a similar development of the outer surface of the container-neck showing the separated or divided spiral threads formed therein;

Fig. 4 is a sectional view taken on the line 4—4 of Fig. 1 showing the locking projections of the cap after the latter has been turned to bring the projections in vertical alignment with their respective openings or passages between the different sections or portions of the spiral thread; and

Fig. 5 is a sectional elevation, similar to Fig. 1, showing a modified form when a double set of locking projections and spiral threads are employed.

Similar numerals refer to similar parts throughout the several figures.

Referring to the embodiment shown in Figs. 1—4 inclusive, the container 6, preferably formed of glass or other suitable material, is of any preferred shape, and has formed immediately below the mouth opening 7 on the exterior walls of the neck 8 a spiral thread 9 shown to be formed of three spaced-apart sections or portions 10, 11 and 12 of substantially the same length as illustrated in Fig. 3. A greater or less number of spaced-apart sections of such separated thread 9 may be employed to suit the requirements. The lower left-hand end of each section 10, 11 and 12 is formed with a vertical rib 13, 14 and 15 respectively to provide a stop and also to prevent the closure cap from being reversely rotated when applied to the containers as will hereafter be described.

The closure cap 16 is formed of sheet metal with the flat top or crown 17 and having the depending shallow flange or skirt 18, the lower edge of which is bent over or curled 5 outward to provide the annular reinforcing bead 19 to strengthen such flange or skirt 18. The skirt 18 is provided with a plurality of bent-in locking projections 20, 21 and 22, preferably of different sizes, and arranged 10 in different planes relatively to the crown 17 and above the bead 19 as shown in Fig. 2. Such projections 20, 21 and 22 are designed to align with, and pass through, the passages or openings 23, 24 and 25 respectively, formed 15 between the sections 10, 11 and 12, when brought into vertical alinement therewith. If desired the projections 20, 21 and 22 may all be of the same size and shape in which case the width of the passages or openings 20, 21 and 22 will be equal. All that is required is that the relative pitches of the sections 10, 11 and 12 and the openings 23, 24 and 25 shall be substantially the same as 20 shown in Figs. 2 and 3.

25 In the modified form shown in Fig. 5, I have illustrated two sets of sections 10, 11 and 12 forming double spiral threads 9 with two superposed locking projections 20, 21 and 22 to engage the under sides 30 of the thread sections 10, 11 and 12, as shown. Such Fig. 5 construction will give an exceptionally secure fastening because of increased frictional engagement between the coacting parts as well as to the low pitch 35 of the divided threads and interlocking projections.

The operation of my improved closure is substantially as follows: The cap 16 is set on the container mouth 7 and rotated as 40 indicated by the arrow in Fig. 4 until the projections 20, 21 and 22 register with the openings 23, 24 and 25 respectively. This vertical alinement or registering of the parts is readily obtained by rotation until each 45 projection 20, 21 and 22 registers and drops through its particular opening 23, 24 and 25 as shown in Fig. 4. The ribs 13, 14 and 15 prevent the cap 16 from being reversely rotated and cause each projection 20, 21 and 50 22 to move forwardly in frictional engagement with the under shoulder of the thread sections 10, 11 and 12 as the cap 16 is further rotated in a clockwise direction as shown in Fig. 4. The ribs 13, 14 and 15 will also serve as a closure stop to prevent 55 the cap 16 from being rotated too far from any undue twisting.

It is manifest that my improved closure may be readily removed and afterwards re-placed on the container 6 to attain re-sealing, and that the relatively low pitch of the divided spiral threads and interlocking projections from the cap skirt 18 produces an increased tightness through wedging, resulting in a closure which will be strong and

durable and sufficiently rigid to withstand all the pressures and strains falling thereon and also preclude any looseness through reverse rotation of the cap.

I claim as my invention:

1. In combination with a container having a divided thread on its neck formed of a number of lengthwise spaced-apart, spirally-extended sections of like pitch each separated by openings of different sizes there-between, a closure having a like number of inturned locking projections of substantially like pitch and of different sizes each to pass through its opening of like size for thereafter simultaneously engaging the under shoulders of its predetermined section upon rotation in one direction. 70

2. In combination with a container having a divided thread on its neck formed of a number of lengthwise spaced-apart, spirally-extended sections of like pitch each separated by openings of progressively increasing sizes there-between, a closure having a like number of inturned locking projections of substantially like pitch and of progressively increasing sizes each to pass through its opening of like size for thereafter simultaneously engaging the under shoulders of its predetermined section upon rotation in one direction. 75

3. In combination with a container having a divided thread on its neck formed of a number of lengthwise spaced-apart, spirally-extended sections of like pitch each separated by openings of different sizes there-between, a closure having a like number of inturned locking projections of substantially like pitch and of different sizes each to pass severally and simultaneously through its openings of like size for thereafter simultaneously engaging the under shoulders of its predetermined section upon rotation in one direction. 90

4. In combination with a container having a divided thread on its neck formed of a number of lengthwise spaced-apart, spirally-extended sections of like pitch each separated by openings of different sizes there-between, a closure having a like number of inturned locking projections of substantially like pitch and of different sizes each to pass through its opening of like size for thereafter simultaneously engaging the under shoulders of its predetermined section upon rotation in one direction, and a combined guide and stop on each section to prevent improper closure rotation in either direction after the several projections have passed through its respective opening between said sections. 100

5. In combination with a container having a divided thread on its neck formed of a number of lengthwise spaced-apart, spirally-extended sections of like pitch each separated by openings of progressively in-

creasing sizes there-between, a closure having a like number of inturned locking projections of substantially like pitch and of progressively increasing sizes each to pass severally and simultaneously through its opening of like size for thereafter simultaneously engaging the under shoulders of its predetermined section upon rotation in one direction, and a combined guide and stop on each section to prevent improper closure rotation in either direction after the several projections have passed through its respective opening between said sections. ¹⁰
